his Attorney.

UNITED STATES PATENT OFFICE

2,239,667

ROAD GUARD

Carl C. Ahles, Albany, N. Y.

Original application July 8, 1935, Serial No. 30,374, now Patent No. 2,204,556, dated June 18, 1940. Divided and this application July 20, 1939, Serial No. 285,631

6 Claims. (Cl. 256—13.1)

The present invention, which is a division of my application, Serial No. 30,374, filed July 8, 1935, Patent No. 2,204,556, issued June 18, 1940, relates to road guards. For a complete understanding of the invention, reference is made to the following description, the accompanying drawing and the appended claims.

In the drawing:

Figure 1 is a partial and compacted side view of a road guard embodying the present invention;

Figure 2 is a plan view illustrating a guard rail supporting bracket embodying the present invention;

Figures 3 and 4 are plan views illustrating modified embodiments of the invention; and

Figure 5 is a view partly in section and partly in elevation of the embodiment of the invention shown in Figure 4.

Referring in detail to the drawing, the present invention is concerned with detail features of the guard rail and its supporting means disclosed in the above identified parent application. The guard rail, as illustrated in Figure 1, comprises a plurality of flexible elements A such as ropes, cables or flexible bands which are adapted to be resiliently mounted by spring brackets, indicated generally at B in Figure 1. The present invention relates specifically to the mounting brackets which are illustrated in detail in Figures 2 to 5, inclusive.

Continuing, in Figure 2 a wood post 13 mounts by means of a bolt 14 a piece of flat metal 15 that is formed into a cylindrical loop with its respective ends overlapped at one side, as at 16. A wire rope 17 extends transversely past the post 13, and clips 18 fasten this rope to the outside of the piece 15 at a position offset from and opposite to the post 13.

In the alternative embodiment illustrated in Figure 3 the post 24 mounts a piece of flat metal 25 that is formed into the form of a loop with its ends 26 curved inwardly so that their outer surfaces contact. A bolt 27 fastens one of these ends to the post 24. A wire rope 28 extends transversely past the post 24 and is fastened to the piece 25 by means of a clip 29 in the same manner as in the case of Figure 2. It is to be noted that in this form the ends of the piece 25 are likewise arranged free so as to permit relative movement of the same, and the mounting of the piece 25 and the connection of the rope 28 to the same is such as to permit such relative movement.

In the embodiment of the invention illustrated in Figures 4 and 5, there is a post 37 to which a

piece of flat spring metal 38 is transversely fastened by means of a bolt 39. This piece is curled into a loop with its end 40 telescoped inside of the same, and its portion opposite the post 37 is provided with a series of apertures 41 arranged in vertical alinement. A plurality of wire ropes 42 extend transversely past this post adjacent these apertures 41, and U-shaped clips 43 engage these strands 42 and have portions 44 which extend inwardly through the apertures 41. These portions 44 are apertured in directions transverse of the loop, or vertically, and are therefore in parallel alinement with the post 37, and a pin 45 is passed transversely through them so as to retain them in position.

I claim:

1. A road guard of the character described, comprising a series of posts, a series of looped resilient sheet metal supports each having a portion adjacent the post rigidly secured thereto, the extremities of each looped support being free to move relatively to each other under impact, a guard rail comprising a plurality of vertically spaced cables extending from support to support and in juxtaposition with the outer surfaces thereof, and respective means mounting each cable on each support with freedom for independent longitudinal sliding movement relative to such support.

2. A road guard of the character described, comprising a series of posts, a series of looped resilient sheet metal supports each having a portion adjacent the post rigidly secured thereto, the terminal extremities of each looped support contacting and movable with relation to one another, a guard rail comprising a plurality of vertically aligned cables extending from support to support, and respective clips interlocked with the supports and loosely embracing the cables to permit them to partake of unrestricted independent longitudinal movement with respect to the supports.

3. A road guard of the character described, comprising a series of posts, a series of looped resilient sheet metal supports each having a portion adjacent the post rigidly secured thereto, the terminal extremities of each looped support contacting and movable with relation to one another, a guard rail comprising a plurality of vertically aligned cables extending from support to support, each support having a series of apertures formed in its portion opposite the post, respective U-shaped clips embracing each of said cables and having portions extending through the apertures in the supports, each clip being per-

forated in a direction substantially perpendicular to the cables, and a retainer pin piercing the perforations in said clips, the parts being thus constructed and arranged to permit free longitudinal sliding movement of the plurality of cables relative to each of said supports.

4. A guard rail construction comprising a series of posts, a series of tube-like sheet metal springs mounted on the posts by means rigidly securing a portion of each spring to a post, the springs being of looped form with their extremities contacting and freely movable relative to one another under force of impact, a guard rail extending alone and in engagement with the front portions of the springs, said guard rail comprising a plurality of vertically spaced flexible cables, the springs being yieldable toward the posts upon impact of a vehicle with the rail and the rail being connected directly to and carried by the springs through the agency of means allowing unlimited sliding movement of the cables relative to the springs, the springs being substantially unyieldable in a vertical direction and thereby maintaining their roadside portions substantially vertical, thus serving to maintain the cables in vertically spaced relationship.

5. A guard rail construction comprising a series of posts, a series of tube-like sheet metal springs mounted on the posts by means rigidly securing a portion of each spring to a post, the springs being of looped form with their extremities contacting and freely movable relative to one another under force of impact, a guard rail extending along and in engagement with the front

portions of the springs, said guard rail comprising a plurality of vertically spaced flexible cables, the springs being yieldable toward the posts upon impact of a vehicle with the rail and the rail being connected directly to and carried by the springs through the agency of apertured clips embracing cables and extending through slots in the springs and including a single retainer pin for each spring common to the clips of all of the cables supported thereon.

6. A road guard comprising a series of spaced posts, a series of resilient sheet metal brackets each having an inner fixed portion rigidly secured to a respective post and a flexible portion spaced outwardly therefrom, each bracket being so shaped in plan and so constructed and arranged that the free extremity thereof can be readily flexed inwardly toward the zone of the post under impact, a guard rail composed of a plurality of cables arranged one above the other and extending from bracket to bracket in contact with the yieldable outer portions thereof, said brackets being adapted to yield upon impact of a vehicle with the guard rail, and retaining members carried by the brackets and making a free sliding fit with the cables so that any cable may move independently of its neighbor with relation to any bracket, said brackets being unyieldable in a vertical direction and thereby maintaining their roadside portions substantially vertical, thus serving to keep the plurality of longitudinally movable cables constituting the guard rail in spaced relation one above the other.

CARL C. AHLES.
